14 Claims. (Cl. 175—294)

This invention relates to electric circuit breakers.

One of the objects of the invention is to provide electric circuit breaker apparatus having provision for the ultra-rapid reclosure of the circuit, for use with either single or polyphase electric plants or circuits.

Another object of the invention is to provide electric circuit breaker apparatus having provision for the ultra-rapid reclosure of the circuit, for use with either single or polyphase electric plants, said apparatus comprising a main circuit breaker of delayed operation, connected in series with an auxiliary circuit breaker which, upon the occurrence of any fault in any one or in several of the phases, operates immediately to break the circuit of the phase or phases affected and then to reclose said circuit, before said main circuit breaker has had time to operate to break said circuit.

The invention, and these and such other objects of the invention as shall hereinafter appear, will be readily understood from the following description, taken in connection with the accompanying drawings, of embodiments of the invention herein given for illustrative purposes, the true scope of the invention being more particularly pointed out in the appended claims.

In the drawings:

Fig. 1 is a view in elevation of a single phase element of the main circuit breaker A and a single phase element of the auxiliary circuit breaker B, both mounted upon a carriage Ch, and a device for connecting and disconnecting A and B.

Fig. 2 shows diagrammatically, mechanism by which the pneumatic operating means of said element B operates the latter.

Fig. 3 shows diagrammatically the mechanical and electrical structure of the pneumatic operating means of element B.

Figs. 4 and 5 show details of the pneumatic operating mechanism of element B.

Fig. 6 shows partly diagrammatically a construction in which the pneumatic operating means for the element B is in proximity to the arc-drawing contacts of the latter; this Fig. 6 also shows diagrammatically the electric actuating means for said pneumatic means.

Fig. 7 is a detail of a part of Fig. 6, on an enlarged scale, and Fig. 7a is a detail of Fig. 7.

Fig. 8 is a further detail of Fig. 6 showing the position of the parts on termination of the circuit breaking operation, also on an enlarged scale.

Fig. 9, on the same scale as Fig. 8, shows the

same parts in the position they occupy on termination of the circuit closing operation.

Referring to Fig. 1, the main circuit breaker A and the auxiliary circuit breaker B are connected to the circuit of the system or line to be protected by suitable conductors en and en₁ respectively and to each other by a suitable device S, said main circuit breaker A being controlled by suitable protecting relays and operated by suitable operating means actuated electrically or by stored up mechanical or pneumatic energy, as hereinafter more fully set forth.

Said auxiliary circuit breaker B, which may be connected (electrically) to and disconnected from said main circuit breaker A by said device S, is of a single or uni-polar controlled type, each of its poles being controlled by special, ultra-rapid operating relays, and operated by an independent pneumatic operating mechanism. Its electric plant may be of the same type and use the same volume of oil as an ordinary circuit breaker, it differing from the latter only mechanically; the differences will be hereinafter fully set forth.

25 The pneumatic actuating means of the arc-drawing contacts of the auxiliary circuit breaker B, actuates said contacts through mechanism which is illustrated in a general manner in Fig. 2. Referring to said Fig. 2, said pneumatic actuating means is diagrammatically indicated at Cp, and operates said contacts by means of a rotary post Co of insulating material, and a system of levers, cranks and ball-jointed links. The parts of this mechanism are always connected, whether 30 the circuit to be protected be closed or opened by the circuit breaker B. Means are provided to damp each movement of this mechanism at its conclusion, said means herein illustratively comprising two shock absorbers am₁ on the movable contact and am₂ on said post Co, and the pneumatic operating means also contributes to the damping action. Said damping means enables said post to be moved very rapidly without risk of breaking it, although it is of porcelain, which 35 is of importance as rapidity of action is an important feature of this mechanism.

40 Referring to Fig. 3, which illustrates diagrammatically the mechanical and electric operating mechanism of the pneumatic operating means, said pneumatic means comprises a reservoir R for compressed fluid, air for example, from which it passes through a valve Va to a cylinder Po through a distributor d₁ which directs it alternately upon the one or the other side of a piston 45 P₁ in said cylinder. The movement is transmit-

ted by a link B_1 and crank M_1 to said rotary post C_0 . Operation of said piston P_1 is started by the opening of said valve V_a by operation of a rapid acting circuit-breaking means, a solenoid B_d for example, the core of which engages lever l and causes the latter to actuate member S to open valve V_a . At the start of the rotary movement of said post C_0 , a cam $C'a$ carried by the latter engages a roller on a pusher p , which engages said lever l to hold said valve V_a open. In the further rotation of said post C_0 , said cam releases said lever l to allow said valve to close at the proper time on reclosing of the circuit of the system by said circuit breaker B . When post C_0 has completed about one half of its rotary movement, a cam $C'a$ carried by said post, acting through a lever L_3 , breaks contact c and circuit of said solenoid B_d . Said contact c is reclosed by an adjustable spring R_1 , but a suitable time lag delays such closure for a time (several seconds for example) sufficient to prevent a second breaking of the circuit of the system by said auxiliary circuit breaker B , should the fault persist. Any suitable time lag device may be used in accordance with my invention, said device herein conveniently consisting of a suitable weight M carried by said lever L_3 and adapted to act in opposition to said spring R_1 .

In case of a fault on said system, a current transformer T_1 the primary of which is in the circuit to be protected, actuates an ultra-rapid operating relay RU which closes a break CR_a in the circuit of another ultra-rapid operating relay CR , which in turn closes a break CR_0 in the circuit of said solenoid B_d , thus causing the latter to operate valve V_a , piston P_1 and post C_0 to operate said auxiliary circuit breaker B to break the circuit of the system to be protected. This closure of said break CR_0 simultaneously closes the circuit of an electro-magnet E of a time lag device serving to close the circuit of a solenoid $B'd$ and effect a delayed operation of said main circuit breaker A to break said circuit of said system to be protected should said fault persist. Said time lag device may conveniently comprise a weight M' , an adjustable spring R' and a movable stop B_u carried by the core of said magnet E .

When the auxiliary circuit breaker B breaks the circuit of said system to be protected, the post C_0 in its further rotation cuts the current of said magnet or solenoid E at contacts CT_1 and said stop B_u drops to prevent closure of the circuit of said solenoid or magnet $B'd$. Upon reclosure of the circuit of said system by said auxiliary circuit breaker B , should the fault still persist, the circuit of electro-magnet $B'd$ will be closed at C' by the operation of RU , CR and E in the continued rotation of C_0 .

The core of magnet $B'd$ acts upon the free end of latch-lever L_4 (Fig. 3), pivoted at L_{40} , and the main circuit breaker A breaks the circuit of said system, cutting at CT_3 the circuit of electro-magnet E , causing B_u to drop and open contacts c' , and also cutting at CT_2 the circuit of $B'd$.

On the other hand, in the case of a simple excess of intensity, rendering the operation of auxiliary circuit breaker B useless, the circuit of electro-magnet $B'd$ may be closed directly by any conventional relay RS , the operation of which is retarded by several seconds.

Fig. 4 shows in detail the pneumatic part of the operating mechanism of the auxiliary circuit breaker B in the position they occupy when the contacts of said circuit breaker are in closed position. Movement of piston P_1 is transmitted to

the rotary post C_0 through link B_1 and crank M_1 . The angle of rotation of said post for the circuit breaking and the circuit closing operations is 60° for each. Distribution of the compressed air is effected by a slide-valve gear comprising pistons P_2 and P_3 , rigidly connected to each other by a rod pivoted at its free end to a beam B_a . Upon breaking of the circuit by said circuit breaker B , compressed air is admitted upon the left side of piston P_1 (see arrow F_2) of cylinder P_0 , and the exhaust is opened at the other side of said piston (see arrow F_3).

On termination of the circuit breaking action of said circuit breaker B the operation of said slide-valve is reversed, thus causing the reclosing of the circuit by said circuit breaker. Furthermore, as the time elapsing between the termination of the circuit breaking operation of said circuit breaker and the starting of the circuit closing operation thereof should be adjustable, said reversed operation of said slide-valve is divided into two periods; the first period lasts during the entire circuit breaking operation of said circuit breaker; the crank M_1 , by means of the link B_2 , swings beam B_a about its fulcrum O_1 , which is held fixed by the joint action of link B_3 , crank M_2 and locking engagement with the latter of the shorter arm of two armed lever L at A_1 . Beam B_a and pistons P_2 and P_3 move from position 0 to position 1; that is to say both the admission of compressed air to and its exhaust from cylinder P_0 are cut off at the end of the circuit breaking operation of said circuit breaker. The second period is that of the circuit reclosing operation of said circuit breaker, by movement of said beam B_a and said pistons P_2 and P_3 from position 1 to position 2, thus tensioning driving spring R_1 . This movement is effected automatically by piston P_4 responsive to air pressure, intake valve V_a having been held open by cam $C'a$ acting on lever l when latch-lever L releases crank M_2 . It is the adjustable retardation of the release of said crank M_2 by said latch-lever L which effects the desired delay of the circuit reclosing operation of said circuit breaker. Any suitable means may be provided to effect said delay in accordance with my invention, the illustrative device herein used for that purpose comprising a dash-pot V_0 , the piston rod of which is adapted to co-operate with said lever L , said dash-pot communicating with said valve V_a by a passage V_{01} provided with a screw controlled vent v_1 for regulating the degree of retardation. Operation of said circuit breaker to reclose the circuit takes place immediately upon the release of said crank by said latch-lever L , said link B_2 thus returning said beam B_a to position 3 by swinging it about its fulcrum O_1 , shifted to O_2 and there held by piston P_4 and the compressed air behind the latter. In this position, pistons P_2 and P_3 have been returned to their position 1, both the intake and the exhaust of said valve gear being closed. Upon termination of the circuit reclosing operation of said circuit breaker, as piston P_4 is held in place by the air pressure, spring R' also remains under tension and the apparatus comes to rest. It is only upon closure of intake valve V_a that the pressure behind piston P_4 drops and that spring R_1 returns pistons P_2 and P_3 to the position 0. The supply of air being thus cut off, said circuit breaker does not operate to break the circuit. The apparatus is thus ready to function again, and the circuit breaker will operate to break the circuit so soon as the intake valve is opened.

As shown in Fig. 5, the circuit breaker B may be locked in its position in which the circuit is closed, by causing direct engagement of roller ro on free end of lever L₁ with free end of crank M₁. As the release of said crank is to take place so soon as the intake valve is opened, such release may be effected pneumatically as shown in said figure by using very light movable parts in order that the operation may be very rapid. The releasing piston actuates the lever L₂ by means of a toggle system comprising pivots a₁, b₁, c₁ which move to positions a₂, b₂, c₂ respectively after said circuit breaker has broken the circuit. Lever L₂ then moves bodily with said crank M₁ to break said toggle and permits said crank to be locked again when said circuit breaker has reclosed the circuit.

The pneumatic operating mechanism of circuit breaker B may be located in proximity to the arc-drawing contacts of the latter. The compressed air will then be conveyed to said operating mechanism through an insulating column I. Fig. 6 shows such an arrangement and also the electric actuating mechanism of said pneumatic operating mechanism, said auxiliary circuit breaker B being shown partially in section. Its movable contact C, which enters the circuit breaking chamber D, is moved by a lever L₁ connected to piston P₁ of said pneumatic mechanism by a link B₁. Slide valves T₁ and T₂ of a slide valve gear admit compressed air at one or the other side of said piston P₁. Air is supplied to said slide valve gear through a controlling valve S which communicates through said hollow column I of insulating material with a compressed air reservoir Ra located at the base of said circuit breaker. Valve S is opened by slight rotary movement of said column I communicated thereto by a piston P₂, both ends of said column being connected to fixed parts of the tubular system by flexible tubular connections F₁ and F₂. To cause said circuit breaker to break the circuit, compressed air is admitted behind piston P₂ which thus, through suitable connections, turns said column I through a slight angle, say about 15°. The upper nose N of said column in rotating first executes a slight lost motion and then engages a pawl M (see Fig. 7) which swings lever X downwardly about its fixed fulcrum O₁ to open valve S. Said nose then automatically disengages said pawl when the latter strikes a fixed stop z (see Fig. 8). See page 4 for detailed description.

Opening of valve S admits compressed air under piston P₁ at a₁ (see Figs. 8 and 9). Said piston rising causes said circuit breaker B to break the circuit. Cam X acting upon roller G keeps valve S open during practically the entire stroke of piston P₁.

During the operation admission of air at a₁ and exhaust of air at a₂ is gradually cut off by slide valves T₁ and T₂ operated by beam U which is connected to lever L₁ by a link B₂ so that movement of said parts is damped. At the end of the circuit breaking operation of said circuit breaker B the different parts occupy the positions shown in Fig. 8.

Closure of the circuit by said circuit breaker B is effected by admission of compressed air at a₂. After a certain lapse of time, which can be regulated and is determined by inflation of a retarding device R, lever L₂ releases beam U, which is then swung upwardly by piston P₃ behind which the air is compressed. Slide valves T₁ and T₂ uncover ports a₁ and a₂ and compressed air is admitted through a₂ behind piston P₁ and

exhausted through port a₁, whereupon the various parts at the conclusion of their movements assume the positions shown in Fig. 9.

During the operation admission port a₂ and exhaust port a₁ are gradually closed by slide valves T₁ and T₂ which are moved downwardly by link B₂. The downward stroke of beam U is limited by the compressed air behind pistons P₃ which prevent said piston from descending further, and ports a₁ and a₂ are kept closed.

When roller G has been returned to its initial position (see Fig. 7) valve S is released and spring r₁ returns it to its seat. Compressed air behind piston P₃ can now escape through the small vent Z₁ of said valve S. The pressure now diminishes and piston P₃ is drawn downwardly by spring r₂, thus swinging beam U downwardly; slide valves T₁ and T₂ uncover ports a₁ and a₂ and the retarding or time lag device R is deflated. When the pressure is sufficiently reduced, lever L₂ is returned to its initial position by spring r₃, thus locking the left end of beam U.

A further cycle of operations is prepared at the upper portion of the apparatus (Fig. 6).

The column I is not returned to its initial position until this cycle of operations is completed. Spring r₄ initiates the operation so soon as the pressure behind piston P₂ is sufficiently reduced. The period of time which elapses before this reduction in pressure occurs is determined by the size of a vent z₂, said size being regulated or adjusted once for all.

Upon the occurrence of a fault, a current transformer T₁ (Fig. 6) actuates an ultra rapid relay RU to close the circuit of a contact device CR the operation of which is also rapid. Said contact device in turn closes the winding B'd of an electro-magnet E_v, which engages a stud S and opens valve V_o, thus admitting compressed air from reservoir Ra to cylinder R_t on left side of piston P₂ which moves to the right against the action of spring r₄ and, through a suitable connection with insulating column I rotates the latter about its axis to break a contact CT₃, thus de-energizing winding B'd. On the other hand in this rotary movement said column closes contact CT₁, thus energizing electro-magnet E of a time lag M'. In its rotary movement said column I also actuates the operating mechanism of said circuit breaker causing the latter first to break the circuit and then to reclose it, thus effecting a complete cycle.

Upon reclosure of the circuit by said circuit breaker, if the fault no longer exists, the contacting device CR is no longer attracted and the circuit of the circuit breaking winding or coil B'd of the triple pole circuit breaker A will not be closed. Column I will return to its initial position shown in Fig. 6 only after a certain lapse of time following closure of the circuit by the circuit breaker as above stated.

Should the fault persist after reclosure of the circuit by said circuit breaker, the relay RU will again close the circuit of said contact device CR which now no longer supply current to said winding B'd, the latter's circuit being open at CT₃, but supplies winding B'd which controls the circuit breaking operation of said triple pole circuit breaker A. The time lag device M', the lag of which is of less duration than the time the ultra rapid circuit breaker B takes to operate to close the circuit, has prepared the closure of the circuit of B'd said device M' having been supplied with current ever since the beginning 75 of the rotary movement of said insulated column

I. Said circuit breaker B has thus remained in circuit-closing position, and the main circuit breaker A is in the position in which the circuit is broken.

In short should a fault persist the circuit of the winding B'd of the electrically controlled valve Ev remains open at CT₃ so long as column I has not returned to its original position, that is to say for a period of time sufficiently long for the main circuit breaker A to break the circuit.

On the other hand in a simple case of excess intensity, rendering unnecessary the operation of the auxiliary circuit breaker B to close the circuit, the current of the winding B'd may be closed directly, for example, by a relay RS the operation of which is retarded for several seconds.

Operation of the apparatus described is as follows: If a fault occurs which for example affects one phase of a line provided at its ends with circuit breaking groups of the kind shown in Fig. 1, each comprising apparatus A and B, the ultra rapid operating relays RU (Figs. 3 and 6) of the apparatus B immediately operate to cause said apparatus B to break the current of the line; then, after the lapse of a certain time from the actuation of said relays, predetermined by adjustment, the two apparatus B are operated in respect to said phase, at both ends of the line to close the current of the line. If now the fault no longer exists, the service of the line is reestablished without the two main circuit breakers A having been operated by their time lag relays to break the line. If on the other hand the fault still persists, the time lag relays of the two main circuit breakers A (M'R', Fig. 3 and M' Fig. 6) act to cause said main circuit breakers A to break the current at the three poles thereof and to disconnect the device S (see Fig. 1) while the current remains closed at the three poles of the auxiliary circuit breakers B.

The invention possesses the following advantages among others. All voluntary operations such as breaking and closing of the circuit with or without synchronisation are effected by normal circuit breakers A, the ultra rapid circuit re-closing apparatus B remaining in circuit closing position, that is to say always ready to operate to break the circuit on occurrence of a fault.

Should a fault persist the two consequent interruptions of the circuit are effected in two absolutely distinct, separate chambers, so that absolute safety is assured. The pressures engendered in the chambers in which the circuit is broken are weaker, and in the case of the second break there is a total absence of gas that could have been ionized on the occurrence of the first break, so that re-striking of the arc is impossible.

The electric installation of a circuit breaker A may be used in the auxiliary circuit breaker B with the ultra rapid reclosing of the circuit, so that the same parts are interchangeable.

Said auxiliary circuit breaker B can be applied to all types of circuit breakers in use, by simple juxtaposition.

Finally the periods of time elapsing between the breaking of the circuit and its reclosing by apparatus B can be regulated or adjusted within wide limits.

I am aware that the present invention may be embodied in other specific forms without departing from the spirit or essential attributes thereof, and I therefore desire the present embodiments to be considered in all respects as illus-

trative and not restrictive, reference being had to the appended claims rather than to the foregoing description to indicate the scope of the invention.

5 Referring to Figs. 7 and 7a, the axis O₂ about which said nose N rotates being in a different vertical plane from that of said nose, the latter, in its swinging movement, as it approaches the arm m₃ of pawl M moves substantially in the 10 plane of said arm, and engages the end of the latter. Said nose thus pushes said pawl to the right (see Fig. 7) and the latter, being carried by cam X and having its arm m₁ in engagement with stop Z₁ on said cam X, swings the latter 15 contraclockwise about its pivot o₁ to cause its free end to push downwardly upon valve stem z₁ of valve S and opens the latter. This operation also swings lever L₁ to cause roller G on the latter to engage the upper cam surface of said 20 cam X. This tends to turn pawl M clockwise by reason of the engagement of said arm m₁ with said stop Z₁. Meanwhile nose N in its further rotation causes lower arm m₂ of said pawl to engage stop z. This combined with the action 25 of stop Z₁ and that of nose N, causes arm m₃ of said pawl to become disengaged from said nose N, and said pawl returns to the position shown in Fig. 8.

I claim:

- 30 1. The combination of a main circuit breaker comprising at least one pole; a circuit to carry a load and controlled by said main circuit breaker; an auxiliary circuit breaker comprising the same number of poles as said main circuit breaker, 35 connected in series with the latter; means for ensuring at will the simultaneous closing or opening of the arc-drawing contacts of all of the poles of said main circuit breaker, the arc-drawing contacts of said auxiliary circuit breaker remaining closed; means, operative in case of an abnormal current in said circuit, to open the arc-drawing contacts of the pole of said auxiliary circuit breaker that is traversed by said abnormal current and then to reclose said contacts 40 after a very short interval; and means rendered operative thereafter, if said abnormal current persists, to open the arc-drawing contacts of said main circuit breaker, the arc-drawing contacts of said auxiliary circuit breaker remaining closed.
- 50 2. The combination of a main circuit breaker comprising at least one pole; a circuit to carry a load and controlled by said main circuit breaker; an auxiliary circuit breaker comprising the same number of poles as said main circuit breaker and 55 connected in series with the latter; operating means including an ultra-rapid relay in the controlling circuit of each of the poles of said auxiliary circuit breaker and rendered operative in case of an abnormal current in said first mentioned circuit for carrying a load, to open the arc-drawing contacts of that pole of said auxiliary circuit breaker that is traversed by said abnormal current and then to reclose said contacts 60 after a very short interval; and means rendered operative thereafter, if said abnormal current persists, to open the arc-drawing contacts of said main circuit breaker, the arc-drawing contacts of said auxiliary circuit breaker remaining closed.
- 65 3. The combination of a main circuit breaker comprising at least one pole; a circuit to carry a load and controlled by said main circuit breaker; an auxiliary circuit breaker comprising the same number of poles as said main circuit breaker and connected in series with the latter; oper-

ating means including an ultra-rapid relay in the controlling circuit of each of the poles of said auxiliary circuit breaker and rendered operative in case of an abnormal current in said first mentioned circuit for carrying a load, to open the arc-drawing contacts of that pole of said auxiliary circuit breaker that is traversed by said abnormal current and then to reclose said contacts after a very short interval; means, including a device to retard its operation, and also controlled by said relay to effect the retarded opening of the arc-drawing contacts of said main circuit breaker to effect the separation of said contacts of the latter if said abnormal current should persist, the arc-drawing contacts of said auxiliary circuit breaker remaining closed.

4. The combination of a main circuit breaker comprising at least one pole; a circuit to carry a load and controlled by said main circuit breaker; an auxiliary circuit breaker comprising the same number of poles as said main circuit breaker and connected in series with the latter; operating means including an ultra-rapid relay in the controlling circuit of each of the poles of said auxiliary circuit breaker; a coil in said controlling circuits to control the opening of the arc-drawing contacts of each of said poles and adapted to be operated by said ultra-rapid relay in case of an abnormal current in said first mentioned circuit for carrying a load, to open the arc-drawing contacts of that pole of said auxiliary circuit breaker that is traversed by said abnormal current and then to reclose said contacts after a very short interval; means for cutting the circuit of the coil of the controlling circuit of a pole after the arc-drawing contacts of the latter have been opened; means to reclose said circuit of said coil after a suitable interval in order to prevent a second separation of the arc-drawing contacts of said auxiliary circuit breaker should the abnormal current persist; means, including a device to retard its operation, and also controlled by said relay, to effect the retarded opening of the arc-drawing contacts of said main circuit breaker to separate said contacts should the abnormal current thus persist, the arc-drawing contacts of said auxiliary circuit breaker remaining closed.

5. The combination of a main circuit breaker comprising at least one pole; a coil adapted to control the simultaneous opening of the arc-drawing contacts of all of the poles; a circuit to carry a load and controlled by said main circuit breaker; an auxiliary circuit breaker comprising the same number of poles as said main circuit breaker and connected in series with the latter; an overload relay operating in case of simple over-intensity in said first mentioned circuit for carrying a load, to close the circuit of said coil and open the arc-drawing contacts of said main circuit breaker, said auxiliary circuit breaker remaining closed; means operating in case of an abnormal current in said first mentioned circuit for carrying a load, to separate the contacts of that pole of said auxiliary circuit breaker that is traversed by said abnormal current and then to reclose said contacts after a very short interval; and means operating thereafter, if said abnormal current persists, automatically to separate the contacts of said main circuit breaker, said auxiliary circuit breaker remaining with its contacts closed.

6. The combination of a main circuit breaker comprising at least one pole; a circuit to carry a load, controlled by said main circuit breaker; an

auxiliary circuit breaker comprising the same number of poles as said main circuit breaker and connected in series with the latter; means for ensuring at will the simultaneous closing or opening of the arc-drawing contacts of all of the poles of said main circuit breaker, the arc-drawing contacts of said auxiliary circuit breaker remaining closed; operating means including an ultra-rapid relay in the controlling circuit of each of the poles of said auxiliary circuit breaker; pneumatic controlling means operatively connected to the arc-drawing means of said auxiliary circuit breaker and including a compressed air intake-valve, opening of which controls the operation of said controlling means, said ultra-rapid relay acting upon said valve in case of an abnormal current in said first mentioned circuit, to open the arc-drawing contacts of that pole of said auxiliary circuit breaker traversed by said abnormal current and then to reclose the said contacts after a very short interval; and means operating thereafter, if said abnormal current persists, to separate the arc-drawing contacts of said main circuit breaker, those of said auxiliary circuit breaker remaining closed.

7. The combination of a main circuit breaker comprising at least one pole; a circuit for carrying a load, controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, the arc-drawing contacts of said auxiliary circuit breaker remaining closed; a pneumatic operating mechanism for each pole of said auxiliary circuit breaker; a lever system for operating the movable contact of each pole of said auxiliary circuit breaker, said mechanism being electrically insulated from said lever system; an insulating column operatively connected to said mechanism and to said lever system to transmit the operative movement of said mechanism to said lever system, and comprising several elements, these elements and those of said lever system, which ensure transmission of the movement, being in continuous engagement without any disengagement on the closing and opening of the arc-drawing contacts of said auxiliary circuit breaker; controlling means for said pneumatic operating mechanism and operating in case of an abnormal current in said first mentioned circuit to open the arc-drawing contacts of that pole of said auxiliary circuit breaker that is traversed by said abnormal current and then to reclose said contacts after a very short interval; and means rendered operative thereafter, if said abnormal current persists, to open the arc-drawing contacts of said main circuit breaker, the arc-drawing contacts of said auxiliary circuit breaker remaining closed.

8. The combination of a main circuit breaker comprising at least one pole; a circuit to carry a load and controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, the arc-drawing contacts of said auxiliary circuit breaker remaining closed; pneumatic operating means for each pole of said auxiliary circuit breaker, said means comprising essentially a cylinder, a

piston in said cylinder and a two-cycle slide-valve gear of which the first cycle, corresponding to the opening of the arc-drawing contacts of said auxiliary circuit breaker, effects the simultaneous closing of the intake and the exhaust of said cylinder on the termination of the opening of said contacts, the second cycle effecting the reclosing of said contacts of said auxiliary circuit breaker; controlling means for said pneumatic operating means, and operative in case of an abnormal current in said first mentioned circuit, to open the contacts of the pole of said auxiliary circuit breaker that is traversed by said abnormal current and then to reclose said contacts after a very short interval; and means rendered operative thereafter, if said abnormal current persists, to open the arc-drawing contacts of said main circuit breaker, the arc-drawing contacts of said auxiliary circuit breaker remaining closed.

9. The combination of a main circuit breaker comprising at least one pole; a circuit for carrying a load, controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, those of said auxiliary circuit breaker remaining closed; pneumatic operating mechanism for each pole of said auxiliary circuit breaker, comprising essentially a cylinder, a piston in said cylinder and a two-cycle slide-valve gear the displacement of which corresponds to the retardation of the reclosing of the contacts of the circuit breaker; mechanical means for ensuring said displacement; an adjustable device for retarding the reclosing of the contacts, adapted to cooperate with said mechanical means; controlling means for said pneumatic operating mechanism, operative in the case of an abnormal current in said first mentioned circuit, to open the contacts of that pole of said auxiliary circuit breaker that is traversed by said abnormal current and then to reclose said contacts after a very short interval; and means rendered operative thereafter, if said abnormal current persists, to open the contacts of said main circuit breaker, the contacts of said auxiliary circuit breaker remaining closed.

10. The combination of a main circuit breaker comprising at least one pole; a circuit to carry a load and controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, the arc-drawing contacts of said auxiliary circuit breaker remaining closed; pneumatic actuating mechanism for each pole of said auxiliary circuit breaker, comprising essentially a cylinder, a piston in said cylinder and a two-cycle slide-valve gear, the displacement of which corresponds to the retardation of the reclosing of the contacts of the circuit breaker; mechanical means for ensuring said displacement; an adjustable pneumatic device for effecting such retardation, adapted to cooperate with said mechanical means; controlling means for said pneumatic actuating mechanism, operative in case of an abnormal current in said first mentioned circuit, to open the contacts of that pole of said auxiliary circuit breaker that is traversed by said abnormal current and then to reclose said contacts after a

5 very short interval; and means rendered operative thereafter, if said abnormal current persists to open the contacts of said main circuit breaker, those of said auxiliary circuit breaker remaining closed.

11. The combination of a main circuit breaker comprising at least one pole; a circuit for carrying a load and controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, 10 those of said auxiliary circuit breaker remaining closed; pneumatic actuating mechanism for each of the poles of said auxiliary circuit breaker, comprising essentially a cylinder, a piston in said cylinder and a slide-valve gear; a spring adapted to be tensioned by the operation of reclosing arc-drawing contacts of said auxiliary circuit breaker and to return said slide-valve to its initial position after reclosing of said contacts; controlling means for said pneumatic actuating mechanism, 15 operative in case of an abnormal current in said first mentioned circuit, to open the contacts of that pole of said auxiliary circuit breaker that is traversed by said abnormal current and then to reclose said contacts after a very short interval; and means operative if said abnormal current persists to open the contacts of said main circuit breaker, those of said auxiliary circuit breaker remaining closed.

12. The combination of a main circuit breaker comprising at least one pole; a circuit for carrying a load and controlled by said main circuit breaker; an auxiliary circuit breaker comprising the same number of poles as said main circuit breaker and connected in series with the latter; means for ensuring at will the simultaneous closing or opening of the arc-drawing contacts of all of the poles of said main circuit breaker, the arc-drawing contacts of said auxiliary circuit breaker remaining closed; pneumatic actuating mechanism for each pole of said auxiliary circuit breaker comprising essentially an intake-valve for compressed air, a cylinder, a piston in said cylinder and a slide-valve gear; means to return said slide valve gear to its initial position upon reclosure of arc-drawing contacts of said auxiliary circuit breaker and closure of said intake-valve; controlling means for said pneumatic actuating mechanism, operative in case of an abnormal current in said first mentioned circuit, 20 to open the arc-drawing contacts of that pole of said auxiliary circuit breaker that is traversed by said abnormal current and then to reclose said contacts after a very short interval; and means operative in case of persistence of said abnormal current, to open the arc-drawing contacts of said main circuit breaker, those of said auxiliary circuit breaker remaining closed.

13. The combination of a main circuit breaker comprising at least one pole; a circuit for carrying a load and controlled by said main circuit breaker; an auxiliary circuit breaker comprising the same number of poles as said main circuit breaker and connected in series with the latter; means for ensuring at will the closing or opening simultaneously of the arc-drawing contacts of all the poles of said main circuit breaker, those of said auxiliary circuit breaker remaining closed; an operating system for pneumatically actuating the poles of said auxiliary circuit breaker, comprising compressed air feeding

means preferably mounted upon the base of said auxiliary circuit breaker and insulated from the contacts of the latter, pneumatic controlling mechanism for the arc-drawing contacts of said auxiliary circuit breaker positioned adjacent to and uninsulated from said contacts and a hollow insulating column connecting said compressed air feeding means with said pneumatic mechanism, the compressed air passing through said column; controlling means for said operating system, operative in case of an abnormal current in said first named circuit, to open the arc-drawing contacts of that pole of said auxiliary circuit breaker that is traversed by said abnormal current and then to reclose said contacts after a very short interval; and means operative in case of persistence of said abnormal current, to open the arc-drawing contacts of said main circuit breaker, those of said auxiliary circuit breaker remaining closed.

14. The combination of a main circuit breaker comprising at least one pole; a circuit for carrying a load and controlled by said main circuit breaker; an auxiliary circuit breaker comprising the same number of poles as said main circuit breaker and connected in series with the latter; means for ensuring at will the closing or opening simultaneously of the contacts of all the poles of said main circuit breaker, those of said

auxiliary circuit breaker remaining closed; a pneumatic operating system for the poles of said auxiliary circuit breaker, comprising compressed air feeding means preferably mounted upon the base of said auxiliary circuit breaker and insulated from the contacts of the latter, pneumatic operating mechanism for the arc-drawing contacts of said auxiliary circuit breaker positioned adjacent to and uninsulated from said contacts, 5 a device for admitting compressed air to said operating mechanism, a hollow insulating column connecting said device with said operating mechanism, the compressed air passing through said column and means for rotating said column about its longitudinal axis; means actuated by rotation of said column to control the operation of said device; controlling means for said pneumatic operating system, operative in case of an abnormal current in said first named circuit, to open the arc-drawing contacts of that pole of said auxiliary circuit breaker that is traversed by said current and then to reclose said contacts after a very short interval; and means operative if said abnormal current persists, to 10 open the arc-drawing contacts of said main circuit breaker, those of said auxiliary circuit breaker remaining closed.
